DIRECTIONAL CONTROL DEVICE FOR ENDLESS CIRCULATION SYSTEM

Isao Inuzuka and Takeo Yuminaka, Katsuta-shi, Japan, assignors to Hitachi, Ltd., Tokyo, Japan, a corporation of Japan

Filed Mar. 31, 1964, Ser. No. 356,284

Claims priority, application Japan, Apr. 2, 1963, 38/16,273

4 Claims. (Cl. 214—16.1)

The present invention relates to a parking building in which parking lots are disposed in vertically spaced apart relation for endless circulation therein, that is, a parking building of so-called merry-go-round type, and more particularly to a control device adapted for an efficient and economical operation of the parking building of the type.

In a parking building of the type, a plurality of parking cages are linked together by means of an endless chain and are driven by a main drive gear connected to a main electric motor by way of a suitably designed reduction gearing. A problem which arises in connection with the operation of such parking system is which direction, either leftward or rightward rotation, must be selected in order to bring an automotive vehicle in a specific parking cage in a shortest possible path to a vehicle entrance and exit which is situated at the lowermost or any other position in the parking building. To this end, various direction selecting devices have been devised heretofore, but all of these have been found defective in their complicated structure.

Therefore, the primary object of the invention is to provide a parking building with parking lots arranged for endless circulation which is provided with an improved and simplified direction selecting device which is adapted to automatically select the direction of movement of the train of parking cages in order to bring a specific parking cage to a desired position in a shortest possible path.

According to the invention, there is provided a parking building having parking lots arranged for endless circulation comprising an outer structure, a plurality of parking cages arranged in vertically spaced apart relation in said outer structure, an endless chain for connecting said parking cages in endless linkage so as to support said parking cages depending therefrom, drive means for rotating said endless chain in either direction, calling means for bringing any specific parking cage among said parking cages to a predetermined position, direction selecting means operative in response to a signal from said calling means for determining the direction of rotation of said drive means, and stopping means operative in response to a signal from said calling means for stopping said specific parking cage at the predetermined position.

There are other objects and particularities of the invention which will become obvious from the following description with reference to the accompanying drawings, in which:

FIG. 1 is a schematic side elevational view of a parking building to which the invention is applied;

FIG. 2 is a schematic front elevational view of FIG. 1;

FIG. 3 is a view showing the structure of one form of a direction selecting device which forms the principal feature of the invention;

FIG. 4 is a perspective view showing another form of the direction selecting device; and

FIGS. 5-7 show a preferred form of a control circuit arrangement according to the invention.

At first, referring to FIGS. 1 and 2, there is shown an outer structure 1 of the parking building in which an endless chain 3 is vertically movably disposed. The endless chain 3 is driven by a main drive gear 2 and

2

supported at opposite ends by follower sprocket wheels 4 and 4'. According to the invention, there are provided sixteen parking cages C₁-C₁₆ which are connected in equally spaced apart relation by the endless chain 3 to form an endless linkage, but it may be understood that the number of the parking cages is in no way limited to sixteen and a greater or a smaller number of cages may be provided as desired. In FIGS. 1 and 2, only four cages out of sixteen are shown, in which the parking cages C₁ and C₁₀ are full and C₂ and C₉ are empty as shown.

FIG. 3 shows the structure of a direction selecting device of the invention, which includes a generally cylindrical bracket B, along the inner periphery of which 5 relaying elements, or switches S₁-S₁₆ according to the embodiment shown, of the same number with the parking cages, or sixteen in this description, are fitted to cooperate with the respective parking cages. It is so arranged that a pitch between any two adjacent switches is proportional to a pitch between the corresponding parking cages. Generally, the parking cages are equally spaced from each other so that they have a substantially equal pitch therebetween.

Levers L₁-L₁₆ are made to protrude from the respective switches S₁-S₁₆ toward the center O of the bracket B, and carry rollers R₁-R₁₆ at the top thereof. The switches S₁-S₁₆ are so designed that they are actuated when the respective rollers R₁-R₁₆ are urged in the radially outward direction or towards the switches. A cam means K 20 of semicircular shape is rotatably disposed about the center O of the bracket B in a manner that the semicircumference thereof abuts the half of the rollers R₁-R₁₆ so as to urge them radially outwardly to thereby actuate the corresponding half of the switches S₁-S₁₆. However, 25 it will be understood that the cam K may be of any shape as long as it can sufficiently actuate the half of the relaying elements of continuous disposition out of the plurality of the relaying elements. Further, it is so designed that the cam K rotates in proportion to the 30 rotation of the endless chain 3, thus the cam K makes one complete turn when the train of the parking cages makes one circulation. In the embodiment shown, the cam K rotates in a direction opposite to that of the endless chain 3. When the parking cages C₁-C₁₆ take 35 the positions as shown in FIGS. 1 and 2, the switches S₁-S₈ in the direction selecting device are open (or closed) and the switches S₉-S₁₆ are closed (or open).

The operation of the direction selecting device will 40 now be explained with reference to control circuits shown in FIGS. 5-7. The circuit of FIG. 5 includes a D.C. source indicated at (+) and (-). Symbols P_a and P_b denote contacts of a lock-out relay, which are arranged to operate in a manner that they are closed 45 and opened under an operable condition in which the parking cages are ready for operation, and opened and closed as soon as the cages start to move, respectively. In order to avoid any confusion, the operating winding of the relay is not illustrated therein. The operable condition referred to above includes stoppage of the parking 50 cages and complete closure of a door between the parking cage and a vehicle entrance and exit. Push button switches B₁-B₁₆ and calling relays A₁-A₁₆ associated with the respective parking cages C₁-C₁₆ are connected to the (+) and (-) terminals of the power source through the contact P_a. Self-holding circuits of these calling relays A₁-A₁₆ are formed by their own auxiliary contacts A_{1a}-A_{16a} and the lock-out relay contact P_b.

The calling relays A₁-A₁₆ are used to set a position 55 of stopping the operation in response to a call and for other purposes including the control and indication of the operation. Therefore, control circuits for such pur-

poses must actually exist, but any illustration and explanation thereof will not be made herein since they are not directly related with this invention. The push button switches B_1 - B_{16} connected to the (+) terminal of the power source through the contact P_a are in turn connected to transfer contacts S_1 - S_{16} through diodes D_1 - D_{16} , respectively. Normally open or make contacts (as shown at *a*) of the switches S_1 - S_{16} are connected to a rightward direction selecting relay R , while normally closed or break contacts thereof (as shown at *b*) are connected to a leftward direction selecting relay L . Actually, the contacts of the switches S_1 - S_{16} shown in FIG. 3 are utilized as the transfer contacts S_1 - S_{16} .

In the circuit diagram of FIG. 6, there are shown contactors **11** and **12** for effecting normal and reverse rotation, respectively, of a main electric motor M . Energization circuits of the respective contactors **11** and **12** are formed by a contact L_a of the leftward direction selecting relay L and a contact R_a of the rightward direction selecting relay R , while they have their self-holding circuits formed by their own auxiliary contacts and a stoppage ordering contact SD . These contactors **11** and **12** are interlocked with each other by their auxiliary contacts 11_b and 12_b .

In the circuit diagram of FIG. 7, symbol M designates the induction motor which is connected through normally open contacts 11_{a2} , 11_{a3} , 12_{a2} and 12_{a3} of the contactors **11** and **12** to a three-phase A.C. source indicated at U , V and W so that any two phases of the three phases can be switched over to rotate the motor in either direction.

When, with the parking cages in the operable condition as shown in FIGS. 1 and 2, it is desired to bring the empty parking cage C_2 down to the vehicle entrance and exit for parking an automotive vehicle therein, the push button switch B_2 may be depressed. Under this state, the switch S_2 in FIG. 3 is inoperative and the transfer contact S_2 in FIG. 5 is closed at its break contact side. Therefore, by depressing the push button switch B_2 , the calling relay A_2 and the leftward direction selecting relay L are energized by circuits of

$$(+)-P_a-B_2 < \begin{matrix} A_2 \\ D_2 \end{matrix} -S_2 \text{ (break contact side)} -L > (-)$$

and the contact L_a of the relay L is closed. Then, the normal rotation contactor **11** is energized by a circuit of $(+)-12_b-11-L_a-(-)$ in FIG. 6 and locks itself through a circuit of $(+)-12_b-11-11_{a1}-SD-(-)$. Therefore, the contacts 11_{a2} and 11_{a3} in FIG. 7 are closed to rotate the induction motor M in the normal direction and the train of the parking cages is made to rotate in the leftward direction as viewed in FIG. 2. When the cage C_2 travels down to the vehicle entrance and exit, the stoppage ordering contact SD is made to open since the calling relay A_2 is in its energized state, but any detailed explanation of such operation will not be made herein. By the opening of the contact SD , the contactor **11** is released to open its contacts 11_{a2} and 11_{a3} and the induction motor M is thereby brought to a halt. With the stoppage of the motor M , the train of the parking cages ceases to move, while at the same time the contact P_a is closed and the contact P_b is opened. Therefore, the calling relay A_2 is deenergized and restored to the normal inoperative state.

Explanation will next be made with regard to a case of bringing down the parking cage C_{15} (not shown in FIGS. 1 and 2) to the vehicle entrance and exit when the direction selecting device is in the state as shown in FIG. 3. The switch S_{15} associated with the cage C_{15} is urged to its operative position by the cam K as shown in FIG. 3. Therefore, it is closed at the make contact side and opened at the break contact side. When, under this state, the push button switch B_{15} corresponding to the parking cage C_{15} is depressed, the calling relay A_{15} is energized by a circuit of $(+)-P_a-B_{15}-A_{15}-(-)$ and the rightward direction selecting relay R is also energized by a circuit of $(+)-P_a-B_{15}-D_{15}-S_{15}$ (make contact side) $-R-(-)$, in

FIG. 5. Therefore, the train of the parking cages now is made to rotate in the rightward direction and the parking cage C_{15} travels the shortest path to be brought to the vehicle entrance and exit.

It will be seen that the cam K in FIG. 3 rotates in either direction in interlocked relation with the movement of the train of the parking cages. Therefore, it is possible to detect the direction in which any parking cage travels the shortest path to reach the vehicle entrance and exit. Suppose, for example, that the parking cage C_{15} has been moved by the above operation from the position of FIG. 1 to be brought to a halt at the lowermost position or the vehicle entrance and exit. Since, in this case, the cam K takes the position at which it urges the rollers R_7 - R_{14} radially outwardly, it can readily be detected that the direction of the shortest path is rightward for the parking cages C_7 - C_{14} and leftward for the parking cages C_{15} , C_{16} and C_1 - C_6 .

Although the description has been made with regard to the direction selecting device of FIG. 3, a similar effect can be attained by a device as shown in FIG. 4. According to the device of FIG. 4, cams K_1 - K_{16} corresponding to the respective parking cages C_1 - C_{16} are coaxially mounted on a rotatable shaft and switches S_1 - S_{16} such as on-off switches are disposed in parallelly aligned relation with the shaft. The respective switches S_1 - S_{16} are arranged to be actuated through springs SP_1 - SP_{16} on the ends of which cam engaging rollers R_1 - R_{16} are fitted.

From the foregoing description, it will be understood that the direction selecting device of extremely simple structure can effectively detect the direction in which any specific parking cage at any position travels the shortest path to reach the vehicle entrance and exit, and thus the operating efficiency of the parking building of the type described can markedly be improved.

What is claimed is:

1. A parking building having parking cages arranged for endless circulation comprising an outer structure, a plurality of parking cages arranged in vertically spaced apart relation in said outer structure, an endless chain for connecting said parking cages in endless linkage so as to support said parking cages depending therefrom, drive means for rotating said endless chain in either direction, calling means for bringing any specific parking cage among said parking cages to a predetermined position, direction selecting means operative in response to a signal from said calling means for determining the direction of rotation of said drive means, and stopping means operative in response to a signal from said calling means for stopping said specific parking cage at the predetermined position, said direction selecting means comprising a cylindrical bracket, a plurality of relaying elements corresponding in number to said parking cages, said relaying elements being disposed along the inner periphery of said cylindrical bracket at pitches proportional to those of said parking cages associated therewith, and cam means arranged to rotate about the central axis of said cylindrical bracket at a reduced rate proportional to the rotation of said endless chain, said cam means being operative to actuate at any one time only half of the continuously disposed relaying element whereby a selected cage can be brought to said predetermined position by the shortest route.

2. In a conveyor system, a plurality of load movers movable in an endless path successively past a station, motive means for effecting movement of said load movers, calling means for energizing said motive means to cause a particular one of said load movers to be transferred to said station, and direction selecting means responsive to said calling means for determining the shortest route of movement of said one load mover to said station, said direction selecting means comprising a plurality of relaying elements each corresponding respectively to one of said load movers and being disposed in a circular configuration facing a central axis in the order of position of

said load movers, a cam element arranged to rotate about said central axis at a reduced rate proportional to the movement of said load movers, said cam element being operative to actuate at any one time only half of the circularly disposed relaying elements whereby a selected one of said load movers can be brought to said station by the shortest route.

3. In a conveyor system, a plurality of load movers movable in an endless path successively past a station, motive means for effecting movement of said load movers, calling means for energizing said motive means to cause a particular one of said load movers to be transferred to said station, and direction selecting means responsive to said calling means for determining the shortest route of movement of said one load mover to said station, said direction selecting means comprising a plurality of relaying elements each corresponding respectively to one of said load movers and being disposed in a circular configuration facing a central axis in the order of position of said load movers, a cam element arranged to rotate about said central axis at a reduced rate proportional to the movement of said load movers, said cam element being operative to actuate at any one time only half of the circularly disposed relaying elements whereby a selected one of said load movers can be brought to said station by the shortest route, said cam element being driven in synchronism with said load movers by said motive means.

4. In a conveyor system, a plurality of load movers movable in an endless path successively past a station, motive means for effecting movement of said load movers,

calling means for energizing said motive means to cause a particular one of said load movers to be transferred to said station, and direction selecting means responsive to said calling means for determining the shortest route of movement of said one load mover to said station, said direction selecting means comprising a plurality of relaying elements each corresponding respectively to one of said load movers and being disposed in a circular configuration facing a central axis in the order of position of said load movers, a cam element arranged to rotate about said central axis at a reduced rate proportional to the movement of said load movers, said cam element being operative to actuate at any one time only half of the circularly disposed relaying elements whereby a selected one of said load movers can be brought to said station by the shortest route, said cam element being driven in synchronism with said load movers by said motive means, said relaying elements being disposed along the inner periphery of a cylindrical bracket with a spacing proportional to the spacing of said load movers.
